BORIS M. ANTIPOVITCH, OF COYOACAN, MEXICO

SWITCHING APPARATUS FOR ELECTRIC SIGNS

Application filed October 30, 1929, Serial No. 403,498, and in Mexico October 8, 1929.

This invention relates to an electric conductor, and particularly to a conductor which constitutes a flasher for electric signs.

An object of the invention is to provide a flasher in which two contact cylinders or heads are connected in parallel to a movable control member, to give an increased variety of lamp pictures or patterns, and an increased number of changes of such pictures or patterns.

Another object of the invention is to so arrange connections to the two contact cylinders or heads that one is operatively connected while the illuminating control pattern on the other is being changed.

A further object of the invention is to so arrange connections to the two contact cylinders or heads that there is an overlapping period during which both cylinders are operatively connected, thus positively avoiding complete darkness of the sign at any time during operative use of the flasher.

In the accompanying drawings Figure I is a diagram of the flasher indicating connections and operating means therefor; Figure II is a vertical sectional view of the flasher and connections; Figure III is a longitudinal sectional view through one of the conducting cylinders or heads of the flasher, showing the means for controlling contact fingers associated therewith; Figure IV is a cross sectional view through the two contact cylinders or heads of the flasher; Figure V is a plan view of the flasher, illustrating particularly the operating connections for the control drum and the contact cylinders; and Figure VI is a front elevation of the timing gears for producing and controlling movement of rotation of the contact cylinders.

In the drawings the reference numeral 1 indicates a lighting circuit, which is desirably a standard alternating current 110 volt circuit. This circuit has one (the ground) terminal connected by means of a brush 2

45 with a complete contact ring 3 on control drum 4. On control drum 4, the body of which is of insulating material, such as bakelite, hard rubber, or the like, are a plurality of arcuate contact strips, or fragmentary conducting rings, *a*, *b*, *c*, *d*, *e*, and *f*, which are

connected with the complete ring 3. Arranged to cooperate with contact strip *a* is a brush 6 connected with a conducting wire 5 terminating in a brush 66, which is arranged to make contact with a contact cylinder or head *A* of brass, or other suitable conducting material. Arranged to cooperate with contact strip *b* is a brush 7 connected with a conducting wire 8, having a brush 9 making contact with a contact cylinder or head *B*, which is also of a conducting material.

Control drum 4 is rotated by any suitable means, such as connections 10 with an electric motor 11 indicated diagrammatically in Figure I of the drawings, and shown in Figure V thereof. Motor 11 is energized by a shunt circuit 12 taking current from the main line 1. The contact cylinders *A* and *B* are also rotated as shown in Figure V with operating gearing 13, which may be desirably operated by connection to the control drum 4 or its actuating connections, as shown.

Each of the contact cylinders *A* and *B* as associated therewith spaced segmental guide members 14 and 15, of bakelite or other suitable insulating material. Through orifices 14*a* and 15*a* in these guide members pass metallic contact fingers 16, each of which has an electrical connection with one of the lamp terminals 18 on contact board 19.

As shown in Figure II of the drawings, each of the terminals on contact board 19 has connections 17*a* and 17*b* with contact fingers 16 associated with both contact cylinders *A* and *B*. Passing over each of the contact cylinders *A* and *B* are pattern strips 20, of paper or the like, which pass over suitable rolls 21. In well known manner, these pattern strips permit certain of the contact fingers to make contact with the bodies of the cylinder, while insulating others from the cylinder with which they are associated. Certain lamps are therefore supplied with current in accordance with the contact of the various fingers 16 on the bodies of contact cylinders *A* and *B*.

Means are provided for removing all the fingers 16 cooperating with each of the contact cylinders from contact with the conducting surfaces thereof. By reference to Figures III

and IV of the drawing such means comprise a plurality of bars 61 of hard rubber or other suitable insulating material, each of the bars 61 being connected with one longitudinal row 5 of fingers 16. Each of the bars 61 is connected by means of two links 22 with collars 23 slidable on the cylinder shaft 24. Contact arms 25 are pivoted to the collars 23 and to a member 26 connected with the plunger of a 10 solenoid 27. Movement of the connection 26 inwardly of the solenoid draws the collars 23 toward each other, thereby raising the bars 61, and removing the fingers 16 from contact 15 with the surface of the cylinder with which they are associated. Conversely outward movement of the plunger brings the fingers 16 into contact with the cylinder.

It will be seen that both the solenoids 27 associated with the contact cylinders A and 20 B are connected with a wire of the circuit 1, and are also connected respectively with brushes 28 and 30 making contact with the contact strips *c* and *d* of the control drum 4, and with the brushes 29 and 31 making contact 25 with contact strips *e* and *f* of the control drum 4. This arrangement permits and produces reversals of current, energizing the solenoids at different periods to act oppositely for raising and lowering the bars 61 and 30 contact fingers 16.

When the position of the control drum 4, during its rotation, is such that both the brushes 6 and 7 are in contact with the contact strips *a* and *b*, both cylinders are in 35 circuit, and are in parallel. At the same time the brushes 28 and 29 are in contact with the strips *c* and *e* of the control drum. This energizes both the solenoids 27 in such manner that the contact fingers 16 associated 40 with each of the contact cylinders A and B may contact the surface thereof. Each of the lamp terminals 18 therefore receives current from either or both the contact cylinders A and B according to the contact of the 45 fingers on each cylinder connected with such terminal, as may be permitted by the pattern papers on the cylinders. The above may be considered to constitute the fully operative, or zero, position of control drum 4. On rotation of control drum 4 continued through 50 5 degrees, the brush 7 cooperating with contact strip *b* no longer contacts the same, and the ground connection to cylinder B is broken. Cylinder B is thus deprived of its 55 current, and is wholly unable to transmit current through any of its contact fingers 16 to the lamp terminals. Such lamps as depend for current upon contact with cylinder B thus become dark, while those depending for current upon contact A remain lighted, according to the pattern papers 20 on the cylinder remaining in circuit.

Upon a further 10 degree rotation of control drum 4, brush 29 passes out of contact 60 with contact strip *e*, and brush 31 contacts

strip *f*. This produces a reversal of current in the solenoid associated with contact cylinder B, and causes the solenoid to act upon connection 26 to draw collars 23 together, and thereby act upon bars 61 to raise all the contact fingers 16 from contact with cylinder B. During the succeeding 15 degrees of rotation of control drum 4, rotation of contact cylinder B is started, and continues during the rotation of control drum 4 through 120 degrees. The cylinder B carrying its pattern paper 20 with it, thus brings a changed pattern into position to cooperate with the contact fingers 16 of that cylinder. Further rotation of control drum 4 through 15 degrees, brings the contact brush 29 again into contact with strip *e*, and carries brush 31 out of contact with strip *f*, reversing the current in solenoid 27 associated with cylinder B, and energizing it to so act that contact fingers 16 associated with this cylinder are again pressed to the surface thereof, in accordance with pattern paper 20. A further rotation of control drum 4 through 10 degrees, causes the brush 7 to again contact strip *b* on the control drum. This again produces illumination of all lamps which depend for current upon contact cylinder B, while current is still supplied by way of contact cylinder A, for a short interval.

The condition described immediately above, may be called the intermediate position, in which current is supplied through both contact cylinders A and B. This condition continues throughout a 5 degree advance of control drum 4.

From the intermediate position, a 10 degree rotation of control drum 4 removes brush 6 from contact with strip *a*, thus breaking the ground connection of the contact cylinder A and interrupting the passage of current by way of that cylinder.

Upon a further 10 degree rotation of control drum 4, the brush 28 ceases to contact strip *c* and brush 30 contacts strip *d*. The action of solenoid 27 associated with the contact cylinder A is thus reversed, to raise the contact fingers 16 cooperating with that cylinder. After a further 15 degree rotation of control drum 4, contact cylinder A is rotated, and carrying with it the pattern paper 20 associated therewith, produces a change in the pattern of that cylinder. Rotation of contact cylinder A continues during the succeeding 120 degree movement of rotation of control drum 4.

A further 15 degree rotation of control drum 4 causes brush 28 to again contact strip *c*, and breaks contact between brush 30 and strip *d*. This reverses the action of the solenoid 27 associated with contact cylinder A to again bring the contact fingers 16 associated with that cylinder again into contact with the surface thereof. The next 10 degrees of rotation of control drum 4 again

brings brush 6 into contact with strip *a*. This completes the operative cycle, the connections being returned to the fully operative, or zero, position above described.

As shown in detail in Figures V and VI, connections 18 may be provided whereby the contact cylinders A and B are rotated from the control drum 4, thus simplifying the timing of these cylinders to produce rotation thereof during the proper periods of a single revolution of control drum 4. The operating connections for the control drum 4 are designated generally by the reference numeral 10. These operating connections 15 comprise a pinion 32 on the shaft of motor 11, whereby movement of rotation is transmitted through gear train 10 to the shaft 33 of control drum 4. On shaft 33 of control drum 4 is a fragmentarily toothed gear 34 20 arranged to mesh during a portion of each revolution thereof with gears 35 and 36 on the shafts 24 of the contact cylinders A and B.

By reference to Figure VI of the drawings it will be seen that the gear 34 on shaft 25 33 of control drum 4 is toothed throughout 120 degrees of its periphery, this 120 degrees are 34a corresponding to the 120 degrees of rotation of control drum 4 referred to in describing the cycle of the flasher. 30 The remainder of gear 34 is untoothed, and can slip on concave faces 37 and 38 of each of the gears 35 and 36. Each of the gears 35 and 36 has two symmetrically arranged toothed portions 39 and 40. The position 35 of the gears shown is that immediately preceding rotation of gear 36 on the shaft of contact cylinder B, with the teeth of the toothed segment 34a of gear 34 about to mesh with the teeth of toothed portion 39 on gear 40. At the end of this meshing engagement gear 36 will have been turned through half a revolution, with the untoothed portion 38 thereof in contact with the gear 34, and the toothed portion 34a of gear 34 lying in the 45 position indicated in dotted lines 34b. Further movement of gear 34 brings its toothed portion into mesh with the toothed portion 40 on gear 35, thus rotating this gear also half a turn during the single complete revolution of gear 34.

It will be readily understood that the provision of two contact cylinders gives a greatly increased variety of pictures, or patterns, through the control of currents to a lamp arrangement, and avoids the necessity of increasing the contact cylinder size to unwieldy proportions, as would be the case if an equal variety were to be obtained by the use of a single contact cylinder. The use 60 of two cylinders, with the arrangement provided, also permits a continuous illumination, there being no interval during which neither of the cylinders is operative. The picture, or pattern, may thus be changed by 65 movement of the pattern paper on one cylin-

der, while current is passing by way of the other cylinder.

The operating connections further provide simple and efficient means for mutually timing rotation of the contact cylinders with 70 the conductors which cooperate with the control drum.

What I claim is:

1. A sign flasher comprising a continuously rotated control drum, a plurality of 75 contact cylinders which are inter-connected in parallel and are in series with said control drum, and connections for intermittently and alternately rotating said cylinders.

2. A sign flasher comprising a continuously 80 rotated control drum, a plurality of contact cylinders, connections for intermittently rotating said cylinders, contact fingers arranged to be moved into and out of contact with said cylinders, and electrical means and 85 connections associated with said control drum for intermittently supplying current to said cylinders and for moving the contact fingers into and out of contact therewith.

3. A sign flasher comprising a continuously 90 rotated control drum, a plurality of contact cylinders which are inter-connected in parallel and are in series with said control drum, and timing gears connected with the control drum for intermittently and alternately 95 rotating said cylinders.

4. A sign flasher comprising a continuously 100 rotated control drum, a plurality of contact cylinders, contact fingers arranged to be moved into and out of contact with said cylinders, electrical means and connections associated with said control drum for intermittently supplying current to said cylinders and for moving the contact fingers into and 105 out of contact therewith, and synchronized connections for rotating the cylinders at intervals during which the contact fingers associated with the cylinders are out of contact therewith.

5. A sign flasher comprising a continuously 110 rotated control drum, a plurality of contact cylinders, contact fingers arranged to be moved into and out of contact with said cylinders, electrical means and connections associated with said control drum for intermittently supplying current to said cylinders and for moving the contact fingers into and out of contact therewith, and timing 115 connections to the control drum for rotating each of said cylinders at intervals during which the contact fingers associated with each are out of contact therewith.

In testimony whereof, I have hereunto set my hand.

BORIS M. ANTIPOVITCH. 125
